UNITED STATES PATENT OFFICE.

GROVER C. HERKENHINE, OF CINCINNATI, OHIO, ASSIGNOR TO THE UNITED STATES CAN COMPANY, OF NORWOOD, OHIO, A CORPORATION OF OHIO.

ASSEMBLING MACHINE.

Application filed December 24, 1924. Serial No. 757,960.

This invention relates to a machine for automatically interfittingly bringing together opposing sheet metal shell sections of substantially concavo-convex configuration for union assembly in such manner that one shell is placed or fitted within or against the other, to form a hollow button-like structure, of a character primarily as is employed to provide ears fixed to opposite sides of a bucket for attaching the bail.

A general object is to provide a mechanism for separately feeding the shell sections by gravity in a selectively progressive order to a station or juncture for interfittingly bringing a pair of mating sections together for union assembly.

Another object is to provide mechanism automatically operable for delivering or feeding the shell sections to the assembly point, with their faces in predetermined relation to one another, so that they may properly engaged.

Another object is to provide means for causing the assembly of the shells to take place within the rotative path of the feeding element in such manner that the element subsequently acts to advance the assembled parts.

A more specific general object is to provide a machine for automatically feeding and assembling the shell sections of bail ears, which after assembly are used upon buckets, pails and like receptacles for attaching bails or handles thereto. Bail ears of this type are each formed of two sections and the sections subsequently placed together and crimped. Heretofore, the sections have been engaged with one another by hand, and then inserted into a chute leading to a crimping mechanism. In the present instance the sections are separately fed from respective hoppers through chutes or ways leading to a common point or juncture and in a relative progressive order for automatically placing or engaging one within the other to form, after crimping together, a hollow button-like structure or bail ear adapted to be secured to opposing sides of a pail or bucket.

A specific object is, therefore, to provide an automatic bail ear feeder and assembly mechanism of the above nature, adapted for use in conjunction with the crimping machine, the assembler mechanism operating to feed the sections from respective hoppers into separate ways or channels leading into

a common channel, the sections meeting at the juncture of the ways for interfitting union assembly and are loosely assembled for advancement to the crimping mechanism.

Another object is to provide a specific 60 form of stop mechanism including lever having abutments for arresting the movement of the sections in predetermined relation to one another, so that the sections are presented to an assembly juncture in a relative progressive order, the mechanism comprising interlocked simultaneously operable trip levers one of which is actuated by the advance of the sections in assembling, the movement of such lever actuating the second 65 to release the succeeding second section for engagement with the next succeeding corresponding first section. Mechanism is thus provided which places the parts together, one part actuating the mechanism to release 70 the other, and the first part being held in a predetermined position, while the second slides toward and into engagement therewith, the relation of the stop and release members being such that as the assembled 75 shell sections are advanced others are conditioned for assembly engagement.

Another object of the invention is to provide means for delivering the shells to the assembler mechanism faced in the proper direction for assembly and to further provide means for the facing and conveying of the two varieties of shells from respective hoppers.

Another object of the invention is to provide means to prevent injury to the shells as they are agitated and turned or faced in the hoppers, for any injury to the shells is apt to cause the shell to jam in the guide ways and interfere with the continuous operation of the machine.

A more general object of the invention is to provide an assembler device in which the two varieties of shells after having been placed in their respective hoppers are thereafter automatically righted and delivered to the chute in proper position, and the pairs assembled and fed to a crimping mechanism.

Other objects and certain features and advantages will appear in the description of the drawings forming part of this application in which drawings:

Figure 1 is a front elevation showing my invention, a portion of the crimping mechanism being shown in conjunction therewith.

Figure 2 is a vertical section through one of the shell holding shell positioning, and feeding hoppers.

Figure 3 is a plan view of the hopper.

5 Figure 4 is a detail fragmentary section substantially on line 4—4 of Figure 2, showing the construction adapted for shell section of one thickness.

10 Figure 5 is a view similar to Figure 4, showing the construction for a shell section of greater thickness.

Figure 6 is an enlarged detail front elevation of the assembler mechanism.

15 Figure 7 is a vertical section substantially on line 7—7, of Figure 6.

Figure 8 is a plan section substantially on line 8—8, of Fig. 7.

20 The numeral 1 generally designates a frame structure adapted to suitably support the various parts of the mechanism, the support for the crimper mechanism not being shown. Upon the top of the frame are mounted hoppers respectively 2, 3, suitably spaced and of the desired capacity, in each of which the respective shells to be ultimately assembled are deposited.

25 The respective shell sections supplied to the hoppers in this particular instance are of a structure when assembled to provide a sheet metal hollow button-like product adapted to be secured to the side of a pail or bucket into which a hooked end of a wire bail is engaged for pivotally anchoring the bail to the bucket. The shell sections may 30 be defined as representing a base section 5 of disk-like form having a plane bottom portion and a flanged rim portion providing an annular recess for receiving an annular flange of a dome-like or cup shaped second or cover section 6, seated into the recess of the base section after which the rim flange of the base section is crimped over upon the annular flange of the cover section to unite and connect the sections together.

35 The present machine merely anchors the mating sections and discharges the same for delivery to the crimper which turns the peripheral rim flange of one the base shell over the annular flange of the cover shell.

40 Mounted upon suitable cross irons below the level of the hoppers is the assembling mechanism, the same being mounted and held upon the frame generally designated at 7 which herein comprises metallic plates so arranged as to provide two vertically disposed channels or chutes respectively 10, 11, one inclined with reference to the other in one plane, joining into a vertically disposed single chute or guide way 12, which leads to

45 the crimping machine generally designated 15. The construction of the crimping machine forms no part of this invention and is, therefore, not described in detail, but the same generally consists of a revolving center wheel and an outer die together forming a

groove, into which the assembled shells are delivered and between which the assembled parts are rolled and the periphery of one element crimped or bent over the other.

50 Chutes respectively 16, 17, lead from respective hoppers and are connected with chutes 10 and 11 leading to the assembly point, the chute 16 guiding the base shell section and the chute 17 the cover shell section. Rotatably journaled in suitable bearings at the front of the frame or support 7 is a shaft 20 extending at both sides of its bearing and at the inner side having a feeding or propelling toothed wheel or member 22, herein having the form of a sprocket 80 wheel, the wheel projecting into the groove 12 through a slot formed by the spaced overlapping plates of the frame 7. The feeding member is so related with reference to the meeting point of the chutes 10, 11, that when the cover shell is disposed for engagement into the base shell one of the teeth 24 of the sprocket lies substantially as shown in dot-and-dash lines in Fig. 7, in a position to intercept a successive cover shell released from 85 in the chute 17 and to gradually advance the assembling shell.

55 The base shell in reaching the juncture of the chutes 10, 11 is held against further descent by an abutment member in proper relation for engagement with the cover shell the base shells being abuttingly engaged in the chute 10 one upon another. The cover shells in the chute 11 are held against descent by a second abutment member, the said abutment members being interlockingly connected for simultaneous operation to release their respective sections as the two assembled shells are advanced by the propelling element. For this purpose the two 60 pivoted levers 25, 26 are employed each pivoted as at 27, 28 adjacent one end, and interlockingly engaged, and each has a free end projecting toward a respective channel, one of the lever ends 32 projecting into the 65 channel 11 and the other 31 engaging against a leaf spring 33, attached by its upper end as at 34 to the rear side of the frame 7.

70 Attached to the bottom end of the spring 33 is a pin 35, which projects horizontally through the side wall of the frame and into and partially across the channel 12, adjacent the meeting point of the channels 10, 11. This pin is adapted for engagement by the 75 edge of the shell section which is held thereby, until force is applied against the ear section by the propelling element, the ear section being at that time engaged within the shell. The end of this pin is suitably 80 beveled or rounded as at 36, so that when the shell is forced downwardly the pin is translated against spring action out of its path. The pin is preferably beveled at an angle 85 to the channel axis and direction of travel 90

of the shell so that the lowermost shell is arrested and momentarily supported until an ear engages it, and then the assembled parts are advanced by the propelling element. When this advance takes place the pin is laterally translated which causes both levers to rock and cause the projecting end 32 of the lever 26, to withdraw and release an ear 6, which drops to an arrested 10 position against the upper side of a tooth of the propelling element, as shown in dot-and-dash lines in Fig. 7, whence the ear is subsequently lowered toward and into engagement with the succeeding shell after it 15 engages the pin 35, the pin immediately resuming its projected position for intercepting this succeeding shell.

The levers of the stop and release mechanism are herein shown as constructed of 20 sheet metal bent into box form at one end to provide reinforcement for pivoting, corresponding edges of the lever, being respectively cut or shouldered as shown at 40, 41, and a spring 42 acting to draw the lever 25 ends together. The levers are thus pivoted and abuttingly opposed and interlocked at one side of their pivots in such manner that when force is applied at the outer end of one the other is simultaneously rocked to cause 30 its outer end to move in an opposite direction. As best shown in Fig. 8, the free end of each lever is curved inwardly toward the other, one end of one of the levers to engage the outer face of the spring and the end of 35 the other lever to project as an abutment within the guiding channel. Although as herein illustrated the pin transmits motion to the lever, the lever itself could be projected into the shell guiding channel and 40 suitably beveled or rounded to obtain the result similar to that of the spring and pin construction, and in this latter instance the levers, and spring 42 only would be needed and used.

45 Thus, means is provided operable by one of the members for causing a release of the second member for bringing the elements into engagement at a given point below the convergently related channels, which comprises a pair of levers each pivoted to its support respectively as at 27, 28, having opposingly faced and related abuttingly engaged shoulders respectively 40, 41, normally flatly engaged and disposed between and 50 spaced from their pivots. The engaged faces normally lie substantially at a right angle to a line parallel with the front or rear face of the support 7. The end of one lever is operable by the translatable abutment pin 35 and the end of the other lever freely projects within the other chute as a stop for the ear, whereby when one lever is moved as the result of the translatable movement of the abutment pin, due to the forcing of a shell 55 member past the pin, the other is corre-

spondingly moved to withdraw its abutment and release the ear. A yieldable spring connection between the levers is provided for normally drawing the same toward one another to dispose the abutments across the 70 path of the shells.

The relations of the channels, pin, projecting lever end, and rotatable feeding element, are such that the assembled shell section when forcibly translated, forces the pin 75 outwardly, thus simultaneously swinging the levers away from one another, causing a release of cover shells in the chute 11 and permitting a cover shell next in order to advance for assembling engagement with a base 80 shell, the levers and pin being immediately returned to normal positions with the abutment ends projecting into respective channels or ways.

The inner surface of the rim flange of the 85 base shell is engaged by the lower outer surface or edge of the annular flange of the cover shell, and as the downward movement of the engaged elements continues the sections are brought together, one within the 90 other, as the result of engagement of the bulb or dome portion of the cover shell by a tooth of the advancing wheel or element, and as the rotation of this element continues a tooth thereof is disposed in the path of the 95 succeeding cover shell to hold the same until the next succeeding base shell is in position against the stop pin.

In order that the shells may be delivered 100 into the chutes 16, 17, in properly righted relation so that when they reach the assembly point, proper assembly may be made, each hopper has therein a device for turning the shells and feeding them into the delivery 105 chutes only when faced in the proper direction. This construction is particularly adapted for concavo-convex circular shell-like bodies.

Referring particularly to Figs. 2 to 5, inclusive, the bottom of each hopper comprises 110 a hollow substantially cylindrical, closed bottom section 50, beveled inwardly and downwardly at its upper inner periphery as at 51, to direct the shell bodies toward the agitator. A shaft 52 is suitably rotatably stepped in the bottom of the element 50, projects upwardly centrally thereof and has keyed thereto a dome-shape or upwardly convex agitator member 53, preferably of 115 hollow construction, to the upper surface of which are attached sweeps 54 for the purpose of continually overturning the blanks to finally dispose their concave faces against the convex face of the dome-shaped rotatable member.

In order to prevent a shell from reaching a delivery chute when it is turned with its convex face toward the dome-shaped member, the member 50 has its inner wall 55 curved at its upper portion as at 56 toward 120 125 130

the rotatable element as shown in Fig. 2, the curve being concentric or parallel with that of the dome, and the vertical lower portion of the dome and the inner vertical side wall 5 portion of the element 50 forming a channel 57 into which when properly turned, the shells are delivered, and around which they travel by rolling upon their edges to a point where they are positively directed down- 10 wardly through an opening 60 into one of the chutes 16 or 17.

Thus the agitator member has a cylindrical lower or base portion merging into a spherical or upwardly convex top portion 15 and the inner surface of the annular member 50 or side wall of the receptacle is correspondingly shaped so as to provide a substantially parallel faced channel, the annulus extending only a relatively short distance 20 upwardly. The edge of the annulus is inclined, from the inner wall surface, upwardly, providing a stop shoulder against which the flange of the shell engages, when 25 the shell is in a reversed position to prevent its descent into the annular feed chamber 57.

Those shells which have not been properly turned or righted cannot enter the annular groove 57 because of their tangent position to the rotating member and impingement 30 against the beveled shoulder surface 51, which relation is shown at the right side of Fig. 2. Therefore, when the flat or convex side of a blank is engaged against the face of the agitator member the blank is prevented from entering the channel and thus no wrongly faced shell may be introduced thereinto. When, however, the shells have 35 been turned with their concave sides against the agitator as shown at right of Fig. 2, they readily slide downwardly into the groove 65 and eventually reach the delivery chute in a manner now to be described.

In order that the shells may not be rolled past the opening 60 leading to the receiving 40 end of the delivery chute, a stop and directing pin 70 is provided which extends horizontally through the side wall of the element 50 and projects into the groove 57 in a position to yieldably intercept the shells. The 45 pin thus functions to prevent a shell from passing beyond the intake end of the chute but is arranged and constructed so that it may yield and cease to intercept the shell and yet direct the same downwardly into the 50 opening. The angle of bevel of the pin and degree of resiliency of the spring 71 determines the yieldability of the pin. The pin 55 may, however, be non-translatably mounted and placed to direct a shell downwardly by 60 impingement and glancing, the pin being placed above the center of the shell, substantially as shown, but spaced to allow the shell to freely pass by and between it and the inclined surface of the opening 60.

65 By this device the saucer-like sections are

positively caused to enter the delivery chute in properly faced or righted condition, in this instance each having its concave face opposed to the concave face of the section in the other delivery chute, the receptacles and 70 mechanisms being designed both for the same style of sections, but being modified according to their thickness. Referring to Fig. 5, it will be noted that the channel 57 has been widened in correspondence to the 75 size of the shell.

Each sweep 54 is cut vertically at the outer side and extends substantially radially toward the outer periphery of the dome-shaped agitator, but stops short of the periphery 80 and has attached at its outer edge a flexible whip-like element 54' as a chain, preferably formed of a few quarter twist links of comparatively light weight. The chain is of such length that the lowermost link or links 85 bridge the groove 57, and lies or lie thereacross against the bevel face 51 of the annulus 50. This arrangement is provided for the following reason:

In experimenting it has been found that 90 when the sweeps alone are used and the same are extended too far toward the periphery of the agitator the thinnest shells 5 are often nicked to such degree as to interfere with their free passage through the chutes 95 or ways leading to the assembler mechanism, thus causing frequent jamming. By shortening the sweeps in outward direction and providing the relatively light flexible whip-like elements, proper turning or facing of 100 the shells is accomplished without nicking or marring. The ears 6 may be fed without the use of the chains apparently because of their greater thickness but the thinner shell-like bodies cannot be successfully fed without the lighter whip-like elements. Any form of whip of the proper weight and length may be used and modified forms of 105 the same are used conformably to the varying size and weight of the thin shells to be 110 agitated and turned.

Thus, the shells lying over or across the cap between the dome-shaped member and the annulus are acted upon only by the whip-like elements and are rolled and turned, not so violently, and are thus eased off into the groove 57, after being properly faced.

The sweeps 54 are preferably concaved on the forward side, so that the shells will be 120 scooped in on that side, when in this instance the agitator dome is rotated in clockwise direction.

The shaft 20 is extended outwardly and is 125 rotatably stepped in a side bearing of the frame 1, projects outwardly therefrom and has non-rotatably attached thereto adjacent the side of the frame a collar 75 against which is placed a disk 76 of friction material and against the outer face of this disk is 130 engaged a hub of a sprocket wheel 77 rotat-

ably mounted upon the shaft having chain connection with the corresponding sprocket 78 keyed to the main power shaft 80 which is rotatably journaled in the frame 1, and 6 has gears 81 thereon meshing with corresponding gears at the lower end of the agitator operating shafts. Suitable pulleys are provided at the outer end of the power shaft.

The sprocket wheel 77 is forced against 10 the washer 76 by a coil spring 82 the tension of which may be adjusted by the nuts 83 which also secure the spring against displacement. At an intermediate point the shaft 20 has a grip 84 non-rotatably attached thereto by which the shaft may be stopped when desired, the tension of the spring being sufficient to suitably drive the shaft under ordinary conditions. Thus, when the operator wishes to arrest the rotation 15 of the feeding wheel 22, he may do so at will.

The base shells 5 descending by gravity in the chute from the hopper 2 are stacked one upon another in abutting engagement 25 with the lowermost shell of the stack held against descent or advance by the pin 35. The pin engages the base shell at a point toward an end of the shell to reduce the timing interval at which the pin is retracted 30 by the shell in the advancing movement of the shells imparted by the sprocket wheel for assembling the shells, and along a line of engagement which is interrupted by the spacing of the non-engaging portion of two 35 adjacent shells, the circular form of the shells providing such spacing. The lowermost base shell as it is arrested by the pin 35 at the juncture of the two chutes is presented in a position for receiving the annular flange of the cover shell and at a lower 40 end thereof so that as the shells are advanced or moved downward as a unit by the sprocket wheel, the cover shell by the wall of the chute is guided and forced from its 45 angular position toward the base shell, for completely inserting the flange of the cover shell into the rim of the base shell. The chute beyond the pin 35 is of a dimension 50 which will confine the shells in the assembled condition.

As the pin is retreated by the moving shells the levers 25 and 26 will be actuated to withdraw the end 32 of lever 26 from the chute 11 to permit the release of a single 55 cover shell, and this release is at a retreat point from the juncture of the two chutes to allow for a progressive order of feed of the base and cover shells to have the base shell 60 reach the assembly station slightly in advance of the cover shell, and insure a proper assembling of the parts.

The rotation of the sprocket is continuous, and the release motion or feed control of the individual shell intermittent and 65 automatically timed by the movement of the

assembled shells. This enables the operation of the machine at a comparatively high speed, and provides for a very definite timed control of the trip release of the individual shells to be assembled.

Having described my invention, I claim:

1. In a device of the class described, a structure providing direct guide channels leading to a common point, a translatable abutment for intercepting and yieldably holding a shell body delivered from one of the channels adjacent the point in a position for assembly engagement by a companion shell body delivered from a second channel, a second abutment for holding the second disk body in its channel at a point above the first body, and means connecting the abutments whereby when the first shell body is advanced the second is released.

2. In a device of the class described, a structure providing a pair of chutes leading to a common point, a feeding element for engaging and translating shell-like elements fed through said channels, after assembly at the point, an abutment member for arresting one of the members adjacent the feeding element in position for assembly engagement by the second shell, means for arresting the second shell, and means operable by said first abutment for actuating the second abutment to release a shell when the first shell is forced past the translatable abutment.

3. In a device of the class described, a structure providing a pair of chutes leading to a common point, a rotatable feeding element having teeth for engaging and translating shell-like elements fed through said channels, after assembly at the point, an abutment member for arresting one of the members adjacent the feeding element in position for assembly engagement by the second shell, abutment means for arresting the second shell, and means operable by said first abutment for actuating the abutment means to release a shell when the first shell is forced past the translatable abutment.

4. In a device of the class described, a structure providing two shell-guiding ways leading to a common point, a translatable abutment element for arresting one of the shell members adjacent and below the meeting point of the ways in position for assembly engagement by a companion shell member arriving from the other way, said element adapted for translation by a shell member when forced thereagainst, a second abutment element for arresting a shell member in the other guide-way at a point above the first shell member and meeting point of the ways, and means connecting the abutments for movement in unison to withdraw the second abutment when the first is translated.

5. In a device of the class described, a

structure providing two shell-guiding ways leading to a common point, a translatable abutment element for yieldably arresting one of the shell members adjacent and below the meeting point of the ways in position for assembly engagement by a companion shell member delivered from the other way, said element having a formed end adapting it for translation by a shell when forced thereagainst, a second abutment element for arresting a companion shell in the other guide-way at a point above the first shell and meeting point of the ways, and means connecting the abutments for movement in unison to withdraw the second abutment when the first is translated.

6. In a device of the class described, a structure providing a pair of shell-guiding ways leading into a third way at a common point, an inwardly spring pressed pin projecting into one of the ways adjacent and below the meeting point, for intercepting and yieldingly holding a shell in position for assembly engagement by a companion shell, and translatable by the forced movement of the first shell to allow its forward movement, a pivoted lever operable by the pin when translated, and a second pivoted lever operable by the first lever, having an end projecting into the other way at a point above the pin for intercepting and releasing the second shell for assembly engagement with the first.

7. In a device of the class described, a structure providing a pair of shell-guiding ways leading into a third way at a common point, an inwardly pressed spring pin projecting into one of the ways adjacent and below the meeting point for intercepting and yieldably holding a shell in position for assembly engagement by a companion shell, said pin having a formed end adapting it to be translated by a forced movement of the first shell to allow advance of the shell, a pivoted lever operable by the pin when translated, and a second pivoted lever simultaneously and positively operable by the first lever, having an end projecting into the other way at a point above the pin for intercepting or releasing a second shell for assembly engagement with the first.

8. In a device of the class described, a structure providing two shell-guiding ways leading to a common point, a translatable abutment element for arresting one of the shell members adjacent and below the meeting point of the ways in position for assembly engagement by a companion shell member, said element adapted for translation by a shell when forced thereagainst, a second abutment element for arresting a shell member in the other guide-way at a point above the first shell and meeting point of the ways, means connecting the abutments for movement in unison to withdraw the second abut-

ment when the first is translated, and means for automatically delivering shells from respective hoppers to corresponding ways relatively faced for assembly at the meeting point of the ways.

9. In a device of the class described, a structure providing two shell-guiding ways leading to a common point, a translatable abutment element for arresting one of the shell members adjacent and below the meeting point of the ways in position for assembly engagement by a companion shell member, said element having a formed end adapting it for translation by a shell when forced thereagainst, a second abutment element for arresting a shell member in the other guide-way at a point above the first shell, means connecting the abutments for movement in unison to withdraw the second abutment when the first is translated, and means for automatically delivering shells from respective hoppers to corresponding ways relatively faced for assembly at the meeting point of the ways.

10. In a device of the class described, a structure providing a pair of shell-guiding ways leading into a third way at a common point, a pin projecting into one of the ways adjacent and below the meeting point for intercepting and yieldably holding a shell in position for assembly engagement by a companion shell, said pin yieldably outwardly translatable and having a formed end adapting it to be translated by the forced movement of the first shell to permit onward shell movement, a pivoted lever operable by the pin when translated, a second pivoted lever interlockingly engaged with and operable by the first lever, having an end projecting into the other way at a point above the pin for intercepting a companion shell for assembly engagement with the first, and means for automatically delivering shells from respective hoppers to corresponding ways relatively faced for assembly at the meeting point of the ways.

11. In a device of the class described, a structure providing a pair of guide-ways leading into a third way at a common point, a translatable pin projecting into one of the ways adjacent and below the meeting point of the ways, for intercepting and yieldably holding a shell in position for assembly engagement by a companion shell, said pin beveled at its inner end for obtaining translation of the pin when a shell is forced through the way, a pivoted lever operable by the pin when translated, a second pivoted lever having an interlocked engagement with the first lever and simultaneously operable therewith and thereby, having an end projecting into the other way at a point above the pin for intercepting and releasing the second shell for assembly engagement with the first, and means for automatically deliv-

- ering shells from respective hoppers to corresponding ways relatively faced for assembly at the meeting point of said ways.
12. In a device of the class described, a structure providing two channels convergent toward and leading into a single channel, a translatable pin normally projecting into the third channel below the meeting point of the channels for arresting and temporarily holding a shell in position for assembly engagement by an "ear" delivered from the other channel, a propelling element having teeth engageable with an ear after its assembly engagement with the shell for propelling the assembled bodies, the next succeeding tooth acting as a stop engageable by the bottom of a succeeding ear for arresting and then lowering that ear to assembly engagement with the next shell, a pivoted lever having an end projecting into the other way for arresting an ear above the shell, means connecting the two abutment members for movement in unison, whereby translation of the assembled parts by the propelling element acts to release and condition a succeeding ear for assembly engagement with the next succeeding shell.
13. In a device of the class described, a structure providing two channels or chutes leading to a common point, a feeding element for engaging and translating the members after assembly at the point, and means operable by one of said members for causing a release of the second member to cause the elements to meet and engage a translatable pin for yieldingly arresting one shell body adjacent the point, comprising a pair of levers each pivoted to a support and having opposingly faced and related shoulders abuttingly engaged, and disposed between and spaced from the pivots, the end of one lever operable by the translatable abutment pin normally projecting into one of the chutes, and the end of the other lever freely projected within the other chute as a movable abutment, whereby when one lever is moved by the abutment pin as one of the shell members is forced past the pin, the other is correspondingly moved to withdraw its abutment and release the other shell, a yieldable connection between the levers and between the pivots and outer ends thereof for normally drawing the levers toward one another, and means for feeding the shells to respective channels in properly faced assembly.
14. In a device of the class described, a structure providing two channels or chutes leading to a common point, a feeding element for engaging and translating the members after assembly at the point, and means operable by one of said members for causing a release of the second member to cause the elements to meet and engage adjacent the point, comprising a translatable pin for yieldingly arresting one shell body, a pair of levers pivoted to the support and having op-
- osingly faced and related shoulders abuttingly engaged, normally flatly engaged and disposed between and spaced from the pivots, the end of one lever operable by the translatable abutment pin normally projecting into one of the chutes, and the end of the other lever freely projected within the other chute as a movable abutment, whereby when one lever is moved by the abutment pin as one of the shell members is forced past the pin, the other is correspondingly moved to withdraw its abutment and release the other shell, a yieldable connection between the levers and between the pivots and outer ends thereof for normally drawing the levers toward one another, and means for feeding the shells to respective channels in properly faced assembly.
15. In a device of the class described, a structure providing two channels convergent toward and leading into a single channel, a translatable pin projecting into the single channel below the meeting point of the ways for arresting a shell in position for assembly engagement by an ear delivered from the other way, a propelling element having equally spaced teeth, one at a time, engageable with the upper portion of an ear after its assembly engagement with the shell, for propelling the assembled bodies and one at a time adapted to act as a stop for holding and lowering a succeeding ear to and into assembly position with a pivoted lever having an end projecting into the second way for arresting an ear, means for causing the two abutments to move in unison toward and away from one another, whereby translation of the assembled parts by the propelling element acts to release a succeeding ear for engagement with the propelling member, preparatory to being lowered to assembly position by the rotative movement of that member.
16. In a device of the class described, a structure providing two channels convergent toward and leading into a single channel, a translatable pin projecting into the single channel below the meeting point of the channels for arresting a shell in position for assembly engagement by an ear delivered from the other channel, a rotatable propelling element having stops engageable one at a time with the upper portion of an ear after its assembly engagement with the shell, for propelling the assembled bodies and acting also for intercepting, holding and lowering a succeeding ear to assembly position, a pivoted lever having an end projecting into the second way for arresting an ear above the propelling element, means for connecting the two abutment members for movement in opposite direction in unison, whereby translation of the assembled parts by the propelling element acts to release a succeeding ear for engagement with the pro-

5 pelling member, preparatory to being lowered to assembly position by the rotative movement of that member, and means for automatically delivering shells from respective hoppers to corresponding channels properly faced for assembly engagement.

10 17. In a device of the class described, a structure providing two channels convergent toward and leading into a single channel, a translatable pin normally projecting into the third channel below the meeting point of the channels for arresting and temporarily holding a shell in position for assembly engagement by an ear delivered from 15 the other channel, a propelling element having teeth, one engageable with an ear after its assembly engagement with the shell for propelling the assembly bodies, the next succeeding tooth acting as a stop engageable 20 by a succeeding ear for arresting and then lowering that ear to assembly engagement with the next shell, and means operable by one of said members for causing release of the second member comprising a pair of levers 25 each pivoted to a support and having oppositely faced and related shoulders abuttingly engaged, disposed between and spaced from their pivots, the end of one lever disposed to be rocked by the translatable pin 30 and the other having an end freely projecting within the ear chute for arresting an ear above the shell, whereby when one lever is moved by the abutment pin as one of the shell members is forced past the pin the other is correspondingly moved to withdraw 35 its abutment and release the other shell.

40 18. In a device of the class described, a structure providing two channels convergent toward and leading into a single channel, a translatable pin normally projecting into the third channel below the meeting point of the channels for arresting and temporarily holding a shell in position for assembly engagement by an ear delivered from 45 the other channel, a propelling element having teeth engageable with an ear after its assembly engagement with the shell for propelling the assembly bodies, the next succeeding tooth acting as a stop engageable 50 by a succeeding ear for arresting and then lowering that ear to assembly engagement with the next shell, means operable by one of said members for causing release of the second member comprising a pair of levers each pivoted to a support and having oppositely faced and related shoulders abuttingly engaged, disposed between and spaced from their pivots, the end of one lever disposed to be rocked by the translatable pin and the 55 other having an end freely projecting within the ear chute for arresting an ear above the shell, whereby when one lever is moved by the abutment pin as one of the shell members is forced past the pin the other is correspondingly moved to withdraw its abut- 60

65 ment and release the other shell, and yieldable connection between the levers and between the pivots and the outer ends of the levers for normally drawing the levers toward one another.

70 19. In a device of the class described, a receptacle having a portion at its lower inner wall curving upwardly and inwardly to a point above the bottom, for obtaining a circular construction overhanging the bottom, and an upwardly faced circumferential stop shoulder, an agitator member rotatable within the receptacle having its outer surface substantially parallel with and spaced from the inwardly curved lower portion of the receptacle to form therewith an annular channel with the circumferential stop shoulder at its entrance, the outer surface of the said agitator member having a convex configuration above the channel, 80 whereby when the convex side of the blank is engaged with the convex surface of the agitator, the blank engages the stop shoulder and is prevented from entering the channel, and whereby when the concave side is 85 engaged against the said convex surface, the blank may enter the channel.

90 20. In a device of the class described, a receptacle having an agitator member rotatably mounted therein, said member having a cylindrical base portion merging into an upwardly directed circular convex portion, an annular member surrounding and spaced from said agitator member to form a channel about the cylindrical and a portion of the 95 convex surface of the agitator, the opposing walls substantially parallel and the upper rim of said annulus inwardly bevelled downwardly towards the agitator, to form a circumferential stop for preventing a wrongly 100 faced cap from entering the channel.

105 21. In a device of the class described, a receptacle having an agitator member rotatably mounted therein, an annular member surrounding and spaced from said agitator member, having its inner surface curving upwardly and inwardly from the bottom, forming a circumferential channel with the agitator member, with the rim of said annular member providing a circumferential stop 110 shoulder at the entrance of the channel, whereby a body of concavo-convex configuration having its concave side engaged with the agitator, is allowed to enter the channel, and whereby when its convex side is engaged 115 with the agitator its periphery impinges the rim of the annulus as a stop, to prevent entrance into the channel.

120 22. In a device of the class described, a receptacle having an agitator member rotatably mounted therein, said member having a cylindrical base portion merging into an upwardly directed circular convex portion, an annular member surrounding and spaced from said agitator member having its inner 125 130

face curving upwardly and inwardly to a point above the bottom, forming a channel about the cylindrical and a portion of the convexed surface of the agitator and providing a stop shoulder at the entrance of the channel, the opposing walls substantially parallel and the upper rim of said annulus inwardly beveled downwardly towards the agitator, a delivery opening leading downwardly from the channel, and a pin projecting into the channel above the delivery opening for directing the shell bodies thereinto as they are rolled theretoward, said pin yieldably translatable for disposal outside of the path of the shell body, to prevent jamming and injury of the bodies.

23. In a device of the class described, a receptacle having an agitator member rotatably mounted therein, said member having a cylindrical base portion merging into an upwardly directed convex portion, an annular member surrounding and spaced from said agitator member to form a channel about the cylindrical, and a portion of the convex surface of the agitator, said annular member having its inner surface curving upwardly and inwardly to a point above the bottom to obtain a constriction overhanging the bottom and to provide a circumferential stop shoulder, the upper rim of the annulus inwardly beveled downwardly toward the agitator, sweep elements extending upwardly from the agitator for turning blanks, and relatively light flexible elements comprising chain links attached at one end to the sweep elements; having their free ends adapted to lie across the channel to forwardly drive and turn the blanks for entrance into the channel.

24. In a device of the class described, a receptacle having an agitator member rotatably mounted therein, said member having a cylindrical base portion merging into an upwardly directed convex portion, an annulus surrounding and spaced from the agitator member to form a channel about the cylindrical and a portion of the convex surface, the internal surface of the annulus curving upwardly and inwardly to a point above the bottom to overhang the bottom, and provide an upwardly facing circumferential stop shoulder, the upper edge of the annular member inwardly bevelled downwardly toward the agitator and flexible elements attached at one end to the convex portion of the agitator adapted to lie across the channel and to agitate, and turn the shell-like bodies when the agitator member is rotated.

25. In a device of the class described, a receptacle having an agitator member rotatably mounted therein, said member having a cylindrical base portion merging into an upwardly directed convex portion, an annulus surrounding and spaced from the agitator member to form a channel about the cylindrical and a portion of the convex surface, said annulus upwardly and inwardly curved at its inner surface to form a constriction overhanging the bottom, and providing an upwardly facing circumferential stop shoulder, sweep elements extending upwardly from said agitator member for engaging and turning the bodies, and flexible whip-like elements attached by one end to said sweep elements having their free ends adapted to lie across the channel for gently tossing, turning and advancing shell-like bodies.

26. In a device of the class described, a pair of guide ways merging into a single discharge way for guidingly bringing a pair of shell sections or the like into opposing assembly engagement, a stop element engaged into said discharge way at the juncture of said guide ways for arresting a pair of engaged opposing shells, and a rotative member, having teeth spaced to consecutively engage the shells in one of said guide ways for advancing the engaged opposing shells to complete the shell assembly and detract said stop element.

In witness whereof, I hereunto subscribe my name.

GROVER C. HERKENHINE.
